CHECK STRAP FOR LOOM PICKER STICKS

Philip G. Rhoads, Wilmington, Del., assignor to
J. E. Rhoads & Sons, Philadelphia, Pa., a partnership

Application February 9, 1949, Serial No. 75,429

5 Claims. (Cl. 139—161)

1

This invention relates to textile machinery and more particularly to an improved check strap used in association with loom picker sticks.

It is conventional practice in loom construction to actuate the shuttle by means of an oscillating stick called the "picker stick," the function of which is to impel the shuttle across the lay or beam at high velocity. It has been found that a loop formed of a leather strap provides suitable means for arresting the oscillations of the picker stick. The requirements of such a strap are that it be inexpensive, easy to install and remove, and that it effectively arrest the motion of the picker stick with a minimum of wear on the picker stick and on the strap. Since the conventional picker stick has straight edges and is pivotally mounted on the loom, it will be understood that opposite edges of the stick in alternate positions of maximum throw are defined by lines which are not vertical but have substantial angularity with respect to each other. In order therefore, to utilize the full width of the check strap in stopping the picker stick and to avoid impact only on the upper edge of the check strap, it has been proposed to cut such check straps in an arcuate manner so that when the strap is secured to the lay, a truncated conical section is formed in which the portions of the strap contacted by the picker stick have substantially the same angle to the vertical as the edges of the picker stick, thus providing full bearing surface between the stick and the strap. An example of such a check strap construction is shown in the Shivell Patent No. 1,993,531.

I have found that substantial beneficial results can be achieved by providing a check strap which may be formed from a straight piece of leather, in which a portion of either or both ends of said strap are provided with a slot that is biased with respect to the center line of the strap. In addition, the edges of the strap adjacent the slot may also be cut on a bias so that the edges are parallel to the center line of the slot.

A primary object of the invention therefore, is to provide a check strap for loom picker sticks having in the flat pattern a central straight pattern characterized by parallel sides, and opposite end portions having edges parallel to each other but at an angle to the central portion so that the desired twist to the strap is quickly provided when the strap is installed on the loom.

A further object of the invention is to provide a check strap for loom picker sticks having in the flat pattern a central straight portion characterized by parallel sides, and opposite end portions

2

having biased parallel edges whereby a truncated cone is formed when the strap is installed on the loom, so that the strap does not interfere with loom structure and the proper twist can be readily ascertained by the loom fixer.

A further object of the invention is to provide a check strap for picker sticks which may be cut from a blank having parallel sides.

A further object of the invention is to provide 10 a check strap for loom picker sticks that may readily be installed on a conventional loom in such a way that the upper edge of the loop formed when the strap is installed, will be below interfering structure on the loom without the necessity of modifying any part of the loom structure.

A still further object of the invention is to provide 15 a check strap for loom picker sticks having in the flat pattern a central straight portion characterized by parallel sides and at least one slot at the end of the strap, the center line of the slot being at an angle to the parallel sides of the central portion so that the loom fixer can install the strap in a biased position with a minimum of effort.

20 A still further object of the invention is to provide a check strap for loom picker sticks which may be cut from a blank having parallel sides and in which maximum bearing surface with the picker stick is provided with a predetermined width at the end of the strap.

25 Further objects will be apparent from the specification and drawings, in which:

Fig. 1 is a perspective showing the upper portion of a loom picker stick and the associated lay on which my improved check strap is installed;

Fig. 2 is an end elevation of the structure of Fig. 1;

Fig. 3 is a flat pattern of the improved check strap;

Fig. 4 is an enlarged detail in elevation showing the picker stick in opposite maximum positions of throw; and

Fig. 5 is a fragmentary sectional detail as seen at 5—5 of Fig. 4.

45 A loom of the type on which my improved check strap is intended to be used, has a picker stick 10 which carries a resilient picker 11 adapted to contact the shuttle 12 and propel it across the lay or beam 13. The lay is provided with the conventional plates and guiding structure 14 and 15 for shuttle 12, as well as a bracket 16 mounted to extend under the lay 13 by means of bolt 17. Bracket 16 has on one side a fixed, depending lug 17a to which the check strap 18 is bolted by means of bolt 19, nut 20, washer 21 and angle

plate 22. The opposite edge of bracket 16 is provided with a lug 23 which adjustably supports angle bracket 24 by means of bolt 25. Bracket 24 serves to control the shape of the strap 18 when installed in position.

In present day loom practice, it is considered essential to provide a vertical bolt 26 which adjustably supports guiding structure 15 and is secured to the lay 13 by means of nut 27. As a result of this requirement of adjustability, bolt 26 frequently extends a substantial distance below bracket 16 and to such an extent that undesirable chafing takes place between the end of the bolt and the strap.

The improved check strap 19 (Fig. 3) is desirably cut from a piece of leather, and for the loom illustrated is 22" long and 2" wide at the center portion. The cut blanks 22" x 2" are then additionally cut at each end for a distance of 3" from the end to provide parallel edges 18a and 18b so that the extreme end 18c of the strap is reduced from 2" to 1 1/4". A slot 18d 1/2" wide and 2" long is cut in the ends of the strap so that the sides of the slot 18d are parallel to edges 18a and 18b. The slots in the preferred form are so cut that the longitudinal center line of each slot is not only biased with respect to the center line of the strap but the slots are biased in opposite directions so that their center lines are not parallel in the flat form but will be parallel when the strap is installed on the loom. Furthermore, it is desirable although not essential, that the angularity of each slot in the case where two slots are provided, is the same with respect to the central parallel edges.

I have also found that in most looms the vertical length of lug 17a and angle plate 22 are fixed so that the width of the strap at the ends is fixed. However, it becomes desirable to provide the maximum width for the strap at the central portion in order that the greatest strength is obtained at the point where the picker stick strikes the strap. It will be apparent from the above illustrative dimensions that the width of the strap at the ends can be made somewhat less than the width of the strap at the central portion, with the result that maximum strap width and strength is achieved when the end width of the strap is fixed and at the same time the flat pattern for the strap is a rectangle.

It will also be understood that the dimensions noted above are by way of example and not by way of limitation. However, I have found in practice that these dimensions operate satisfactorily to fulfill the objects of the invention.

When the strap 18 is installed on bracket 17a, the strap 18 is looped so that the ends of the strap overlap each other, as shown in Fig. 5. Edges 18a and 18b are then pressed so that they register with the corresponding edges on the opposite end of the strap. This in turn causes the slots 18d, 18d to register with each other. Bolt 19 and plate 22 may then be installed and tightened securely in place. When the strap 18 is thus installed, it has been found that the shape of the loop formed by the strap and assisted by angle bracket 24, is such that the ends 30 and 31 of the loop automatically provide a biased inside surface that is parallel to the outer edge 10a of the picker stick when in its extreme position. This result enables full bearing surface between the edge 10a and the strap 30, thereby greatly lengthening the life of the check strap.

In addition, my construction enables the upper edge 18e of the check strap to be on a sub-

stantially lower plane than the upper edges 18b, 18b of the strap (Fig. 2). This feature eliminates chafing and interference between edge 18e and bolt 26 so that a further increase in the life of the check strap is achieved without the necessity of modifying any structure of the loom.

Fig. 4 shows how the strap 18 is displaced alternately when contacted by the picker stick at the end of its stroke. The full lines represent the 10 position of the stick and strap when the stick is in its extreme left position and the broken lines show the corresponding position of the loop and stick when the stick is in the opposite extreme 20 position. Since it will be apparent from Fig. 4 that the strap 18 is secured at only one point in the loop (namely bolt 19) the opposite side of the strap which abuts bracket 24 slides back and forth on the bracket at a relatively high speed when the stick alternates between the two positions shown in Fig. 4. This is why it is especially 25 important to avoid any contact between bolt 26 and the upper edge 18e of the strap. It has been found that straps having their upper surface 18e in a substantially flat plane chafe excessively and break long before they are worn out, merely with contact with the picker stick.

While it might be possible to reduce chafing by lengthening bracket 17a or by shortening bolt 26, such redesigning would not be economically practical because the cost of furnishing and installing 30 the modified parts on the thousands of looms in current operation would be far greater than the cost of more frequent renewal of straps. Therefore, it must be further pointed out that my improved strap fulfills the distinct need for reducing strap renewals by prolonging the life of the straps without the necessity of redesigning any part of the loom.

It will be understood that slots 18d, 18d may be 40 provided in either or both ends of the strap and that the bias of edges 18a, 18b is primarily to serve as a guide in clamping the strap so that the proper twisting of the strap may be achieved. Obviously it is not essential that the sides 18a and 45 18b be parallel to the center line of slot 18d but it is important that the center line of at least one slot 18d is set at an angle to the center line of the strap body so that an adjustment of the strap can readily be made without altering its 50 biased position when clamped to bracket 17a.

It will thus be apparent that I have provided an improved check strap for loom picker sticks which is characterized by maximum strength with the minimum amount of material, and which greatly 55 lengthens the life of the strap when installed on conventional looms by eliminating chafing. In addition, the loom fixer is enabled to install the strap with the desired bias in a minimum of time.

Having thus described my invention, I claim:

1. A check strap for loom picker sticks comprising a single length of leatherlike material having a straight portion with substantially parallel edges, and at least one slot near the end 60 of said length, the center line of the slot being substantially biased with respect to the center line of the straight portion.

2. A check strap for loom picker sticks comprising a unitary single length of leatherlike material having a central straight portion with substantially parallel edges, a portion at each end of the strap having edges parallel with each other and biased with respect to the edges of the central straight portion, and a slot in each of said 65 end portions, the center lines of each slot also

being biased to the edges of the straight central portion.

3. A check strap for loom picker sticks comprising a unitary single length of leatherlike material having a straight portion with substantially parallel edges, at least one end portion having edges biased with respect to the edges of the straight portion, and a slot in said end portion, the center line of the slot also being biased to the edges of the straight portion.

4. A check strap for loom picker sticks comprising a unitary single length of leatherlike material having a central straight portion with substantially parallel edges, a portion at each end of the strap having edges parallel with each other and biased with respect to the edges of the central straight portion, and a slot in each of said end portions, the center lines of each slot also being biased to the edges of the straight central portion so that the slots register with each other when the strap is looped and the ends placed in side-by-side relation.

5. A check strap for loom picker sticks comprising a unitary single length of leatherlike material having a central straight portion with substantially parallel edges, a portion at each end of the strap having edges parallel with each other and biased with respect to the edges of the central straight portion, and a slot in each of said end portions, the center lines of each slot also being biased to the edges of the straight central portion and parallel to the edges of the end portions.
